US0D1032403S

(12) **United States Design Patent** (10) **Patent No.:** **US D1,032,403 S**
(45) **Date of Patent:** **** Jun. 25, 2024**

(54) **BUCKLE**

(71) Applicant: **ZEDEL**, Crolles (FR)

(72) Inventor: **Paul Petzl**, Barraux (FR)

(73) Assignee: **ZEDEL**, Crolles (FR)

(**) Term: **15 Years**

(21) Appl. No.: **29/738,988**

(22) Filed: **Jun. 22, 2020**

(30) **Foreign Application Priority Data**

Dec. 20, 2019 (EM) 007435789

(57) **CLAIM**

The ornamental design for a buckle, as shown and described.

DESCRIPTION

FIG. 1 is a front, left-side, bottom perspective view of the buckle, showing the new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof; and,

FIG. 8 is a rear, right-side, top perspective view thereof.

The broken lines depict parts of the buckle that form no part of the claimed design. The dot-dash lines in FIG. 1 represent a claim boundary and form no part of the claimed design.

1 Claim, 6 Drawing Sheets
